UNITED STATES PATENT OFFICE.

NORMAN COLLINS, OF LONDON, ENGLAND, ASSIGNEE TO WALISHAW CLOCK COMPANY LIMITED, OF LONDON, ENGLAND.

ELECTRIC CLOCK.

1,363,841.

Specification of Letters Patent. Patented Dec. 23, 1920.

Application filed July 25, 1919. Serial No. 313,169.

To all whom it may concern:

Be it known that I, NORMAN COLLINS, a subject of the King of Great Britain and Ireland, residing at London, in the county 5 of London, England, have invented certain new and useful Improvements in Electric Clocks, of which the following is a specification.

This invention relates to electric clocks 10 of the type in which the oscillations of the pendulum are maintained by an electromagnet attracting an armature attached to the bob of the pendulum or vice versa, and in which a pivoted pawl or wiper is carried 15 by the pendulum or by a part oscillating therewith, so that it passes to and fro over a pallet or block mounted upon a spring, in such a manner that the pallet is only engaged by the pawl or wiper when the amplitude 20 of the oscillations falls below a pre-determined minimum, whereupon the wiper engages with the pallet and causes the spring to come against a moving contact carried by the pendulum, thus completing 25 an electrical circuit, energizing the magnet and causing the armature to be attracted in order to keep the clock in motion.

In the practical method of working clocks 30 of the before mentioned description, various drawbacks or imperfections have been observed.

For instance with the known constructions, the contact has not been broken at precisely the proper instant, the result being 35 that the electromagnet attracts the armature for too long a time, putting a certain amount of brake upon the pendulum, thus leading to loss of electrical energy and consequent exhaustion of the dry cell or the like, sooner 40 than would otherwise be the case.

In some instances also the current has been conducted down the pendulum to the contact device, an arrangement which is found undesirable as it is likely to lead to 45 fusing and consequent breakage of the circuit.

My present invention relates to an improved construction in which the contact making mechanism is so constructed and arranged 50 that the circuit is broken exactly when the pendulum swings through the vertical, so that no brake is put upon its upward movement.

I also prefer to provide two separate spring arms or their equivalents, insulated 55 from one another and each in connection with one pole of the battery. Both these arms are controlled by the pallet and the wiper, so that when they are operated thereby they come into contact with a pin or the 60 like carried by the pendulum or by a part moving therewith through which the circuit is completed.

In order that my invention may be clearly understood I will now proceed to describe, 65 by way of example, one method of carrying it into effect, with reference to the accompanying drawing, in which:

Figure 1 is a view of the operating parts of the movement with the device carrying 70 the pallet and contact making spring in the raised position.

Fig. 2 is a similar view showing the relative position of the parts when the oscillation of the pendulum falls below a certain 75 amplitude.

Fig. 3 is a similar view showing the position assumed by the parts when the contact making device is depressed by the 80 wiper.

Fig. 4 is a fragmentary under plan of Fig. 3.

The same letters of reference are employed to denote the same parts in all the 85 views.

a is the usual swinging arm provided with pins or projections *b* which engage the pendulum or a part oscillating therewith. *c* is a freely moving hanging pawl, usually termed the wiper, carried by the arm *a*. *d* 90 is a post or support projecting from the framework and carrying a light flat spring *e* of suitable springy metal or other appropriate material. *f* is a stop for limiting the downward movement when required, of the strip *e*. *g* is a projecting block or pallet carried by the strip *e*. This pallet is provided with a notch *h* and is curved or beveled on the face *h*, as shown clearly in the drawing. *m* is a block of electrically insulating material mounted on the under side of the strip *e* which block in turn carries two springy strips *n* and *p* of conducting material, shaped as shown. The ends *q* and *r* of these strips are connected electrically 100 to a battery *s* or other source of power and

in this circuit is disposed the magnet *t* which restores the amplitude of the oscillation.

In the drawing the magnet is merely indicated diagrammatically as its use and location are perfectly well known. Under ordinary circumstances it is placed vertically below the bob of the pendulum and the armature is mounted on the pendulum; but of course a combination of magnets may be used which exert an attractive force vertically below the axis of suspension of the pendulum. The outer ends *u* and *w* of the strips are arranged as shown, and it is to be observed that they terminate in the vertical line. *x* is a projecting pin of electrically conducting material carried by the arm *a* in such a position that it rubs against the springs *n* and *p*, when they are depressed.

The action of the mechanism will be readily understood.

When the pendulum swings through an arc of predetermined amplitude, that is above a certain minimum, the lower end of the hanging wiper *c* trails up the surface *h* of the pallet *g* and passes entirely over the said pallet swinging down on the other side as indicated by the arrow *z*. When however the amplitude of the oscillation falls below the predetermined minimum, the end of the wiper *c* does not entirely clear the pallet *g*, but at the end of the upward swing remains in the notch *h* as seen at Fig. 2, the result is that upon the downward swing, the wiper causes the strip *e* to be depressed, thus bringing down the ends *u* and *w* of the springs *n* and *p* into the path of the pin *x*, which as it is carried along by the arm *a* causes a rubbing electrical contact to be made thus completing the electric circuit and energizing the magnet *t*.

Owing to the fact that the springs *u* and *w* terminate in the vertical line, the circuit is broken at the instant that the pendulum passes through the vertical, and no brake is put upon the armature due to the continuance of the flow of the current.

It will be understood that the particular arrangement just described and illustrated in the accompanying drawing is given merely by way of example, as various modifications may be made without departing from the principle of my invention.

For instance the wiper, as in the older constructions, may cause only one contact making spring such as *u* to be operated, the circuit being completed through the pendulum, but in any case the spring is made of such length that the circuit is broken as the pendulum passes through the vertical. It is obviously not essential to terminate the contact making spring or springs in the vertical line, the essential point being that the rubbing contact making pin oscillated by

the pendulum shall leave the contact making spring or springs as the pendulum swings through the vertical.

Instead of using a spring contact making arm or arms, I may use one or more rigid spring controlled arms for the rubbing contact.

What I claim as my invention and desire to secure by Letters Patent of the United States of America, is:—

1. In a horological instrument, a frame, a swinging member supported thereby, a pawl pivotally carried by said member, a movable contact, a fixed contact on said member, an operating strip carried by said frame for operating said movable contact, and a block on said operating strip projecting into the path of travel of said pawl and adapted to be engaged by the free end of said pawl when the amplitude of oscillation of said swinging member falls below a predetermined minimum for forcing said strip downwardly to bring said movable contact into the path of travel of the contact on said swinging member, substantially as described.

2. In a horological instrument, a frame, a source of current, an electric motor in electrical connection therewith, a swinging member supported by said frame and adapted to be oscillated by said motor, a pawl pivotally carried by said member, a movable contact, a fixed contact on said member, a resilient operating strip carried by said frame for operating said movable contact, and a block on said strip projecting into the path of travel of said pawl and adapted to be engaged by the free end of said pawl when the amplitude of oscillation of the swinging member falls below a predetermined minimum for forcing said strip downwardly to bring the movable contact into the path of travel of the contact on the swinging member to close the circuit to said motor, substantially as described.

3. In a horological instrument, a frame, a swinging member supported thereby, a pawl pivotally carried by said member, a movable contact, a fixed contact on said member, an operating strip carried by said frame for operating said movable contact, and a block on said operating strip projecting into the path of travel of said pawl and adapted to be engaged by the free end of said pawl when the amplitude of oscillation of said swinging member falls below a predetermined minimum for forcing said strip downwardly to bring said movable contact into the path of travel of the contact on said swinging member, said contact being made and broken when the swinging member is in substantially vertical position, substantially as described.

4. In a horological instrument, a frame, a swinging member supported thereby, a pawl

pivotedly carried by said member, a movable contact, a fixed contact on said member, and means extending into the path of travel of said pawl and adapted to be engaged by the 5 free end thereof when the amplitude of oscillation of the swinging member falls below a predetermined minimum for forcing the

movable contact into the path of travel of the contact on said swinging member, substantially as described.

10

In testimony whereof, I have hereunto subscribed my name.

NORMAN COLLINS.
